UNITED STATES PATENT OFFICE.

RUDOLPH A. MILLER, OF CINCINNATI, OHIO, ASSIGNOR TO THE HEEKIN CAN COMPANY, OF CINCINNATI, OHIO, A CORPORATION OF OHIO.

SYNCHRONIZED PRESS AND OVEN CONVEYER.

Application filed March 24, 1923. Serial No. 627,514.

To all whom it may concern:

Be it known that I, RUDOLPH A. MILLER, a citizen of the United States of America, and resident of Cincinnati, in the county of 5 Hamilton and State of Ohio, have invented a new and useful Improvement in a Synchronizing Press and Oven Conveyer, of which the following is a specification.

An object of my invention is to provide 10 means for synchronously operating a press for printing sheet metal and the like in conjunction with a conveyer for receiving the printed material and for carrying the printed material through an oven employed for baking the imprint.

Another object of my invention is to provide a device that will permit independent operation of the conveyer and oven.

Another object of my invention is to provide 20 a mechanism of the type referred to wherein the conveyer may be actuated directly from the press yet wherein the conveyer will continue to function although the press may be stopped whereby to avoid damage to the printed material in the oven.

These and other objects are attained by the means described herein and disclosed in the accompanying drawings, in which:

Fig. 1 is a fragmental side elevation of a 30 press, a conveyer and oven together with a portion of a synchronizing mechanism all of which form details of my invention.

Fig. 2 is a continuation of the oven and the synchronizing mechanism shown in Fig. 1.

Fig. 3 is a fragmental side elevation showing the opposite side of the press shown in Fig. 1.

Fig. 4 is a fragmental end elevation of the 40 oven and synchronizing mechanism shown in Fig. 2.

Figs. 5 and 6 are diagrammatical views showing the wiring of the circuits employed with the device embodying my invention.

The press 7 may be of any suitable type 45 such as is used for applying enamel or the like to metal plates or sheets. The press 7 is operated from a motor 8, see Fig. 3 in any suitable manner and by any suitable means whereby the sheets may be passed between the cylinders or drums 9 and 10 for the 50 reception of imprints, and from which drums the sheets pass to cooperating belts 11, 12 and 13 for carrying the sheets to a conveyer 14 adapted to receive the sheets and to carry

same through an oven 15. A shaft 16 driven from the motor 8 and extending longitudinally of the press 7 drives a second shaft 17 extending longitudinally of the conveyer 14 of an oven 15. The shaft 16 may be driven from the motor 8 in any suitable manner such as by means of a worm wheel 18 carried by the shaft 16 and a worm 19 carried by the shaft 20 driven from the motor 8. The shaft 17 may in turn be driven from the shaft 16 in any suitable manner such as by means of sprockets 21 and 22 carried by the shafts 16 and 17 respectively, and about which sprockets a chain 23 extends. The shaft 20 may be driven from the motor 8 in any suitable manner, and a suitable clutch 60 may be employed for controlling the transmission of rotary motion to the shaft 20 from the motor 8. A lever 24 is connected with the referred to clutch in any suitable manner such as by means of a connecting rod 25, a crank 26 and a link 27, and serves as a means for operating the clutch. The connecting rod 25 carries an electrical contact 28 for engagement upon the electrical contact 29 carried by the frame of the press 7. The parts are so related that when the lever 24 is actuated so as to render the shaft 20 quiescent, the contacts 28 and 29 are brought into electrical communication upon 70 one another whereby to complete a circuit passing through a switch 30 carried by the standard 31 intermediate the press and the conveyer, see Fig. 1, and a motor 32 for actuating the conveyer 14. From the foregoing it will be apparent that if the switch 30 is set properly so that when the circuit is completed through the contacts 28 and 29, the motor 32 will continue the movement of the conveyer 14 as the shaft 17 becomes 80 quiescent due to the disconnection through the clutch controlling transmission of power from the motor 8 to the shaft 20. It will also be apparent that after the circuit passing through the switch 30 is broken after 85 the circuit had been completed through contact 28 and 29 the motor 32 will become inoperative whereupon the conveyer 14 will become stationary. By referring to Figs. 2 and 4 it will be apparent that motion from the shaft 17 is imparted to the conveyer by means of an eccentric 33 mounted on the rear end of the shaft 17 operating upon an adjustable link 34 having its upper end connected to a bell crank lever 35 upon one arm 90

of which lever is carried a pawl 36 for operation of a ratchet wheel 37 mounted on the shaft 38 carrying sprockets 39. The sprockets 39 carry endless chains 40 forming part of the moving portion of the conveyer. The shaft 38 may be adjusted longitudinally of the brackets 41 supporting the shaft 38, in any suitable manner such as by mounting the shaft 38 in a suitable block 42 adjustable longitudinally of a slot 43 formed in the bracket 41, by means of a suitable screw 44 extending through the frame 41 and operative upon the block 42. The bell crank lever 35 is mounted upon the shaft 38 for oscillatory movement. A second bell crank lever 45 is mounted upon the shaft 38 for oscillation and carries a pawl 46 for engagement upon the ratchet wheel 37. The bell crank lever 45 is connected with eccentric 47 by means of a longitudinally adjustable link 48. The eccentric 47 is driven from the motor 32 by any suitable gearing mechanism, for example as shown at 49.

25 The conveyer 14 comprises the endless chains 40 carrying substantially U-shaped frames 50. The adjacent frames 50 are adapted to receive the printed sheets or plates from the conveyer 13 and to carry the sheets through the oven 15. Heat may be applied to the oven 15 in any suitable manner. It should be noted that at the receiving end of the conveyer 14, the endless chains extend about a sprocket 51 of a diameter such that the outer edges of the frames 50 are spaced at a considerable distance for the reception of the sheets from the conveyer 13. The chains pass from the sprockets 51 to suitable drums 52 that serve to position the chains between themselves and the sprockets 39 so that the frames 50 extend in substantial parallelism as they pass between the sprockets 39 and drums 52. As the frames pass about the sprocket 39 they discharge the sheets under the influence of gravity.

30 By reference to Figs. 5 and 6 it will be apparent that at the close of day, an operator would actuate the lever 24 after the last of the sheets have passed through the press 7, thereby disconnecting the press from the motor by means of the clutch 27 and rendering the press quiescent simultaneously and closing the circuit embracing the auxiliary motor 32 whereupon the auxiliary motor would actuate the conveyer and thereby feed the prints or sheets through the oven. After the motor 32 has been embraced in a complete circuit by the engagement of the contacts 28 and 29 the operator would open the circuit through the motor 8. After the last of the sheets have passed through the oven the operator would open the circuit through the motor 32 by means of switch 30. On the fol-

lowing morning the operator would actuate the lever 24 so as to render the motor 8 operative upon the press, thereby disconnecting the contacts 28 and 29. The operator would then actuate the switch 30 and position the contacts of the switch 30 so that when subsequently the lever 24 is actuated to render the motor 8 inoperative upon the press, the auxiliary motor 32 would be again brought into action.

What I claim is:

1. The combination of a press, a conveyer, means for driving the conveyer from the press an auxiliary means for actuating the conveyer upon the press being rendered inoperative and means for simultaneously rendering the press inoperative and the auxiliary means operative.

2. In a device of the class described the combination of a press, an oven, a conveyer for receiving work from the press and for carrying the work through the oven, means for driving the press, means actuated from the press driving means for actuating the conveyer, an auxiliary means for actuating the conveyer normally inoperative upon the conveyer and means for rendering the press actuating means inoperative and for rendering the auxiliary means operative upon the conveyer.

3. In a device of the class described the combination of a press, driving means for the press, a conveyer for receiving work from the press, means driven from the press for actuating the conveyer, a normally inoperative auxiliary means for actuating the conveyer and means for simultaneously rendering the driving means inoperative upon the press and rendering the auxiliary means operative upon the conveyer.

4. In a device of the class described the combination of a press, driving means for the press, a conveyer for receiving work from the press, means driven from the press for actuating the conveyer, a normally inoperative auxiliary means for actuating the conveyer, means for rendering the driving means inoperative upon the press and rendering the auxiliary means operative upon the conveyer, and means for rendering the auxiliary means inoperative upon the conveyer independent of the means controlling transmission of power from the press driving means to the press.

5. The combination with a press and driving means therefor, of a conveyer for receiving sheets from the press and comprising endless chains and sheet-supporting means carried by the chains, sprockets and shafts for the chains, a driven shaft operative from the press, an eccentric on the driven shaft, a ratchet operative on one of the shafts for the chains, a connection between the eccentric and the ratchet for transmitting motion from the driven shaft.

to the shaft associated with the ratchet, an electric motor, a shaft driven by the motor, an eccentric mounted on the motor-driven shaft, a second ratchet on the shaft carrying the first ratchet, a connection between the second-mentioned eccentric and ratchet, an electrical contact, a lever for rendering the driven shaft inoperative and carrying a contact for engagement with the

first-mentioned contact upon movement of 10 the lever for rendering the driven shaft inoperative, and an electrical circuit embracing the contacts and the motor.

In testimony whereof, I have hereunto subscribed my name this 20th day of March, 15 1923.

RUDOLPH A. MILLER.
